UNITED STATES PATENT OFFICE.

BURDETTE D. LA FORCE, OF OTTUMWA, IOWA.

TONSIL ENUCLEATOR.

Application filed May 18, 1927. Serial No. 192,271.

My invention pertains to a tonsil enucleator and is a type of surgical instrument in the class of tonsilectomes or tonsil snares, the primary purpose of which is to effect a 5 removal of the faucial tonsils or other more or less inaccessible tissues.

A general object of my invention is a surgical instrument suitable for the above purposes and other operations in which hæmostasis and amputation in rapid succession are 10 necessary for their successful completion.

A further object of my invention is the construction of a tonsil enucleator or similar surgical instrument having a blade of the 15 character of a hemostat blade with a metal loop operating therewith, the loop functioning somewhat as a snare and pressing the tonsils or other tissues to be removed against the hemostat blade, thereby crushing the tissues before the severing and thereby performing a substantially bloodless operation.

Another object of my invention is the construction of a tonsil enucleator or similar surgical instrument having the hemostat blade 25 and the wire loop or snare associated, whereby the snare can be slid lengthwise and manipulated independently of the blade to engage and grip the tonsil or the like and by means of a trigger the snare may be operated 30 to press the tissues between the blade and such snare and this pressure may be increased by a screw threaded device, pressing the tissues between the blade and the snare, and then when desired the blade and the snare 35 may be slid longitudinally, severing the tonsils or other tissues.

My invention will be more readily understood from the following description and drawings, in which

40 Figure 1 is a side elevation of my tonsil enucleator.

Figure 2 is a longitudinal section on the line 2—2 of Fig. 3 in the direction of the arrows.

45 Figure 3 is a plan view taken in the direction of the arrow 3 of Fig. 1.

Figure 4 is a front end view taken in the direction of the arrow 4 of Fig. 1.

50 Figure 5 is a rear elevation taken in the direction of the arrow 5 of Fig. 1.

Figure 6 is a plan view similar to Fig. 1 showing the parts of the implement in a different position, as when crushing the tissues prior to their severance.

Figure 7 is a plan view of the instrument 55 showing the position after severing the tonsils and moving the hemostat blade and the loop.

Figure 8 is a section on the line 8—8 of Fig. 7 in the direction of the arrows. 60

Figure 9 is an enlarged detail section on the line 9—9 of Fig. 6 in the direction of the arrows.

Figure 10 is a plan view of the loop or snare.

Figure 11 is a transverse sectional detail on 65 the line 11—11 of Fig. 7, showing the positions of the catch.

The fixed structure of my device is formed substantially as follows:

It includes a main supporting arm 11, 70 which forms a slideway, this arm having an operating end 12 with a longitudinal slot 13 through such end. Such end has opposite projecting sides 14, the slot being sufficiently wide to pass through said projecting sides. 75 The supporting arm has a longitudinal groove 15 positioned substantially centrally and has an abutment end 16 with an opening 17 therein. A handle 18 extends downwardly from the end of the supporting arm adjacent the abutment end and is provided with a brace 19 which is adapted to fit over the top of the hand between the thumb and the first finger.

A sliding bar 20 is mounted on the arm 11 85 having a pair of pins 21 or the like extending into the groove 15. This bar is flat and has serrations 22 at its rear end extending outwardly beyond the body of the bar. The distal end of the bar forms a hemostat blade section 23, this extending through the slot 13 from the rear end 24 which stops the bar by a ridge 25 transversely on such bar, and the forward end of the hemostat blade preferably has vertical corrugations 26 and a slightly convexed edge 27, as indicated most clearly in Fig. 7, and a deep concave groove 27' (Fig. 9).

On top of the slideable bar, having the hemostat blade, is positioned an operating 100 bar 28 which is held in position by means of a slide clamp 29, this having a base 30 which fits underneath the supporting arm 11 and has a longitudinal ridge 31 engaging one side of such supporting arm. The vertical side 32 105 of the slide clamp extends upwardly along the sides of the supporting arm 11 and the slideable bar 20 and is secured to the edge of the

operating bar 28 by screws 33 or the like. A trigger 34 is rigidly secured to the base 30 of the slide clamp.

The slide bar has a yoke 35 at its outer end, 5 this yoke having a slot 36 therethrough, and a loop 37 is secured in such yoke, the loop forming a snare. This loop has two parallel sides 38 and a base end 39, the end being flattened, as indicated in the cross section of 10 Fig. 2, so that it may be entered edgewise in the slot 36 of the yoke 35 and when turned in the horizontal position the loop is prevented from being drawn out of such slot. The distal end 40 of the loop is preferably 15 corrugated on the inside surface, as indicated at 41, forming part of a snare to cooperate with the hemostat blade.

Extending rearwardly from the operating bar is a screw 42, this screw extending 20 through a catch 43 which is loosely mounted on the screw and is adapted to fit between the abutment end 16 of the supporting arm and the end 44 of the slideable bar 20 having the hemostat blade. This catch is flat on the 25 lower surface 45 so that it may be swung by the handle 46 from a position with the handle inclined downwardly and between the abutment 16 and the end 44, or when swung upwardly into the position shown in Figs. 8 30 and 11 the catch allows the upper surface of the slideable bar 2 to slide underneath, as is indicated by the relative position of such catch in Figs. 1 and 7.

The screw 42 slides through the opening 35 17 in the abutment 16 and has a knob 47 at its end to allow pressure thereon. A nut 48 is threaded on the screw and has radial spokes 49 to allow ready pressure thereon in screwing the nut tight against the abutment 16.

40 The mechanical manipulation of my enucleator is substantially as follows:

The slide bar 20 may be moved longitudinally of the supporting arm 11 by gripping the serrations 22 when the handle 46 is in a 45 vertical position and when this bar is thrust outward into the position shown in Fig. 2 so that the ridge 25 engages the rear part 24 of the operating end of the device, such bar is in its extreme position. In order to hold the hemostat blade 23 in this position the handle 46 of the catch is dropped to one side or the other so that the catch fits between the abutment end 16 of the supporting arm and the end 44 of the slideable bar 20. This, therefore, 50 restrains the rearward movement of the hemostat blade. The loop or snare may be manipulated by first screwing the clamping screw 48 towards the knob 47 of the operating bar and by means of the trigger 34 thrusting 55 the loop outwardly through the sides of the slot 13, the sides 38 of such loop passing on the outside of the hemostat blade, as illustrated in Fig. 7.

To draw back this blade the first finger of 60 the hand may pull on the trigger 34 which

gradually pulls the snare inwardly, the operating bar sliding on the slideable bar 20 which, as above mentioned, is held stationary, being so held by the catch 43. The trigger may be drawn inwardly until the distal end of the 70 loop engages the end of the hemostat blade. Then to give increased pressure, the nut 48 is jammed tight against the abutment end 16 of the supporting arm 11, the operator utilizing the spokes 49 in turning this. Then, 75 when desired, the catch may be released from the back of the slideable bar 20 by shifting same to the upper position and the hemostat blade with the loop like snare may then be drawn rearwardly freely by the trigger 34, 80 these moving together or, if desired, by further jamming the nut 48 against the abutment.

In manipulating the enucleator in a surgical operation, for instance to remove the 85 tonsils, the faucial tonsil is engaged by the metal loop by pressing the distal end of such loop when in its outer position against the posterior pillar of the throat and the faucial tonsil. Pressure is made in a direction to 90 force the loop in back of the tonsil and by manipulation of the instrument the tonsil is made to bulge the anterior pillar of the throat forward. When the anterior pillar is seen to bulge forward, it is pressed upon by 95 the first finger of the unoccupied hand of the operator to cause the tonsil to slip through the loop of the snare. When it is determined that this has been accomplished, the trigger is pulled, which brings the loop tightly 100 against the tissue of the tonsil and compresses this tissue between the hemostat blade and the distal end of the loop. Considerable pressure may be brought to bear by pulling on the trigger but, as this usually is not sufficient to thoroughly crush the tissue, the nut 105 48 is operated as above explained and when the tissue has been thoroughly crushed the tonsil may be grasped by forceps. The catch which holds the operating bar and the hemostat blade in place is released and either the trigger is pulled by the finger or the nut 48 is turned, which procedure severs the tonsil 110 from the tissues that have been held in the hemostat. These several operations may be 115 performed with my instrument to effect the complete enucleation of the tonsil without hemorrhage.

It will be noted that the grooves through the operating end 12 and the projecting ends 120 14 of the supporting arm give a support to the loop or snare and considerably stiffen the wire so that this wire has a relatively long longitudinal support.

In my invention a hemostat may be considered as formed by a fenestra in which one part, that is a relatively stationary part, is formed by the hemostat blade 23 and the other by the loop or snare, this forming a fenestra or window when open. Thus the tonsil may 125 130

be introduced in this fenestra when the window structure is open and the tissues squeezed by closing such window structure, and finally amputated by a complete pressure between 5 the hemostat blade and the end of the loop, and by the retraction of the hemostat blade in such a manner that the wire forming the loop will break through the weakened tissues when it is further retracted through the 10 slotted part of the frame.

It may be more readily understood how the 15 hemostasis takes place in such an operation by those not especially familiar with such operations by knowing that when a blood vessel is thoroughly crushed and its lumen is closed and more or less glued together by pressure that the blood in the lumen of the vessel at the place where the crushing is produced and adjacent thereto becomes coagulated and blocks the flow of blood in the 20 vessel thus preventing bleeding.

In reviewing some of the important features of my invention it will be observed that 25 a mechanism is provided whereby the tissues to be severed are crushed directly in the place where they are finally completely severed which it is believed is accomplished in a unique manner.

Another very important feature of my 30 improved instrument is the very simple manipulation necessary to accomplish the operation above described.

When it is understood that many very 35 badly diseased tonsils are very deeply imbedded in the tissues, and which fact makes their removal more difficult, it will be readily appreciated by operators to have an instrument whereby such tonsils may be removed in a simple and bloodless manner.

The simple manner of the removal of the 40 tonsil with my improved instrument is especially due to the provision of a mechanism whereby the engagement of the tonsil is effected by lassoing it with a wire or the like 45 loop which is held and supported in an open manner. By being held and thus supported the wire or the like loop will stand the pressure necessary to press it down around the tonsil. Having the tonsil once engaged in the 50 provided lasso the other unique features are provided in a very simple manner of manipulation to thoroughly crush the tissues about the tonsil and to sever them where they have been crushed and in this way performing a 55 bloodless operation.

A special feature of my invention is that 60 the heavy wire loop is supported at the sides where it passes through the guide slots in such a manner that this cannot collapse. This distinguishes from the type of flexible snare in which a wire is contracted, squeezing the tonsil and eventually cutting the same. With 65 my construction I have the benefit of the snare-like loop in that my wire loop may be readily fitted behind the tonsil.

Another characteristic feature of my invention is that the snare-like rigid loop is contracted around the tonsil, crushing the tissue of the tonsil between the wire of the loop and the dull edge of the hemostat blade. 70 Therefore, by this construction and the manner of retracting the loop, the tissue may be thoroughly crushed against this hemostat blade, and after sufficient crushing, the tissues are cut in the exact place in which they 75 have been crushed. This, to a great extent, prevents a hemorrhage.

Another characteristic feature of my invention is that the hemostat blade and the loop, when the tissues are crushed therebetween, may be retracted into the guide structure at the end of the instrument, thus entirely clearing the loop from the severed tonsil. 80

My invention also distinguishes from the 85 tonsillotomes in which the tonsil is severed by a moving knife-like construction having a sharp blade, and in some of these, the tonsil is held in a rigid position by a holding device so that the blade may press the tonsil against 90 this holding structure, but in this case there is no effective crushing of the tonsil at the very place at which it is subsequently severed.

While the description of the instrument herein shown, described and claimed, in a 95 preferred form, is especially designed to enucleate the faecal tonsil in a bloodless manner, it will be easily understood that instruments embodying the unique features herein described may be provided in instruments 100 made smaller or larger to be adapted to such parts as the nasal cavities, the rectum, or abdominal cavity, and the like, for the removal of tissues and abnormal growths in a bloodless manner. 105

Various changes may be made in the principles of my invention without departing from the spirit thereof, as set forth in the description, drawings and claims.

I claim:

1. A surgical instrument having a dull hemostat blade and a non-collapsible snare like wire loop, means to move said blade and loop relatively to each other to crush tissue between the end of the blade and the 115 wire loop, and to sever such tissue.

2. A surgical instrument having a dull hemostat blade and a non-collapsible snare like wire loop, slidably mounted one relative to the other to engage and crush tissue between the end of the blade and the wire loop, and means to slide the hemostat blade and the loop together with tissue compressed therebetween. 120

3. A surgical instrument having a supporting structure with a dull hemostat blade slidably mounted thereon, a wire loop like non-collapsible snare also slidably mounted on the supporting structure to slide relative to the hemostat blade to crush tissue between 125 130

the end of the blade and the end of the snare, and means to hold the hemostat blade stationary during the sliding of the snare.

4. A surgical instrument having a supporting structure with a sliding bar having a dull hemostat blade and a slideable operating bar having a non-collapsible snare like wire loop, means to latch the slideable bar with the hemostat blade in one position, and means to slide the snare with the hemostat blade latched to compress tissue between the end of the blade and the snare.

5. A surgical instrument, as claimed in claim 4, means to unlatch the slideable bar and to allow sliding of said bar and hemostat blade and the snare, with tissue pressed between the blade and the snare.

6. A surgical instrument having a supporting structure with an operating end having a slot, a slideable bar having a dull hemostat blade fitting in said slot, a non-collapsible wire loop like snare slideable through the said slot, and means to slide the snare to compress tissue between same and the end of the hemostat blade.

7. A surgical instrument having a supporting structure with an operating end having a slot, a slideable bar having a dull hemostat blade fitting in said slot, a non-collapsible wire loop like snare slideable through the said slot, means to slide the snare to compress tissue between same and the end of the hemostat blade, and means to latch the slideable bar with the hemostat blade in the slot, said means being releasable to allow movement of the bar and the blade with the snare, having tissue crushed between the blade and the snare.

8. A surgical instrument having a supporting structure, an operating end having a slot, a slideable bar having a hemostat blade fitting in said slot, a non-collapsible snare like wire loop extending through the slot in said operating end, means actuated by a finger to slide the snare relative to the said blade to crush tissue between the blade and the snare, and manually operated means independent of the finger operated device to increase the pressure of the snare against the blade.

9. A surgical instrument, as claimed in claim 8, a latch mounted in the supporting structure positioned to engage the slideable bar and to hold same with the blade in the slot, said latch being releasable to allow sliding of the said bar under said latch.

10. A surgical instrument having a supporting arm with an abutment at one end and an operating end having a slot, a slideable bar having a hemostat blade mounted on the supporting arm, the blade fitting in the said slot, with means to limit the forward movement of said blade in the slot, an operating bar slideably mounted on the supporting bar, a wire loop like non-collapsible

snare connected to the operating bar and extending through the said slot, means to latch the slideable bar with the slideable bar with the hemostat blade in the slot, and a trigger device connected to the operating bar to slide same relative to the slideable bar to compress tissue between the hemostat blade and the end of the snare.

11. A surgical instrument, as claimed in claim 10, and a screw threaded mechanism operatively connected to the operating bar and causing an increased tension on the loop like snare, the said latch being releasable from the slideable bar to allow simultaneous movement of the hemostat blade and the snare.

12. A surgical instrument comprising in combination a supporting arm having an operating end with a slot therethrough, a slideable bar mounted thereon, having a hemostat blade fitting in the said slot, an operating bar slideable on the slideable bar and having a yoke at its outer end with a slot therethrough, a loop forming a snare, having one part fitting in said yoke and insertable through the said slot in the yoke, the loop extending through the slot in the operating end of the supporting arm, and means to slide the slideable bar to compress tissue between the loop and the hemostat blade.

13. In a surgical instrument a supporting arm having an operating end with a slot therethrough, a slideable bar having a hemostat blade fitting in the said slot, an operating bar sliding on the slideable bar and having a yoke at its outer end, with a slot in said yoke, a loop forming a snare having a flattened end, the said flattened end being insertable through the slot in the yoke, two sides of the loop extending through the slot in the operating end, and the distal end of the loop having internal corrugations.

14. In a surgical instrument a hemostat blade, having means to support same, a snare like loop slideable in relation to the said blade, the blade having an edge with a concave groove, means to draw the distal end of the loop into the said groove.

15. A surgical instrument comprising in combination a supporting arm having a pistol grip, an operating end on said arm having a slot therethrough, an abutment extending upwardly at the other end, a slideable bar mounted on the supporting arm, interacting means to guide the slideable bar, said bar having a hemostat blade fitting in the said slot, an operating bar slideable on the slideable bar and having a loop like snare connected thereto, the snare extending through the said slot, a screw extending rearwardly from the operating bar through the abutment, a catch having sides partly encircling the said screw and loosely fitting thereon, the said catch in one position fitting between the end of the slideable bar and the abutment and in another

position allowing movement of the slidable bar underneath said catch, a nut on the end of the screw to bear against the said abutment, and a trigger means to slide the operating bar.

16. A surgical instrument having a hemostat blade and a snare like loop, means to move said blade and loop relatively to each other to hold and to crush tissues therebetween, and means to cause said loop to sever the tissues at the very place they have been so held and crushed.

17. A surgical instrument, having a supporting structure with a slot constructed in the forward end thereof, said slot provided to admit of a wire loop or the like to slide through in a more or less open position, means to propel the said wire loop through the said slot to sever tissues engaged in the loop, a hemostat blade with its forward or operating end engageable in said slot, means for locking and releasing said blade in said slot, means for retracting said loop onto the operating end of said hemostat blade to crush tissues therebetween, means provided on the forward end of said frame to support the wire loop or the like in an open position, independent means to slide, lock and release said loop and said hemostat blade in operative position to accomplish holding and crushing tissues engaged therebetween, and means to accomplish the severance of said tissues at the place they have been crushed.

18. A surgical instrument, a supporting frame with handle attached thereto, with a blade having a wire like loop at the forward or operating end, said blade slidable on said frame, a hemostat blade slidable on said frame, means for sliding the said wire like loop and the forward or operating end of the hemostat together to crush tissues therebetween, means for retracting said hemostat end from the inside surface of the said loop, and means for sliding the said wire like loop past the forward end of said frame to amputate tissues therebetween or held or engaged in the said loop.

19. A surgical instrument, as claimed in claim 18, the inside surface of the end of the wire like loop and the end of the hemostat blade being provided with more or less corrugations or teeth like construction provided to increase the hemostatic effect of said parts.

20. A surgical instrument having a supporting structure with an operating end having a slot, the forward or operating end of said structure being flattened with projecting ends extending therefrom, one on either side of said supporting structure, the inner edge of said projecting ends being grooved, a slidable bar having a hemostat blade fitting in said slot, a loop like snare slidable in a more

or less open position through said slot, means to slide the snare to compress tissues between same and the hemostat blade, independent means to lock and release said hemostat blade from its place in said slot, and means to slide said loop through said slot to completely sever tissues engaged in the loop.

21. A surgical instrument having a hemostat blade and a non-collapsible snare-like wire loop, means to move said loop onto the end of the hemostat blade to hold and crush tissues therebetween, and means to finally sever said tissues so held in the very place where they have been crushed.

22. A surgical instrument having a dull hemostat blade and a non-collapsible snare-like wire loop, means to maintain the loop in a widely distended position, means to slide such distended loop onto the end of the hemostat blade to thoroughly crush tissues between the blade and the loop, and means to sever such tissues at the very place where they have been crushed.

23. A surgical instrument in which is combined a hemostat and a snare, a supporting structure, a wire bent to form a loop with prolonged ends, a metallic bar, means in the form of two prolongations on the supporting structure to support the wire loop in a distended manner, a slot in the end of the supporting structure through which the wire loop may be movably engaged, means to lock the metallic bar in a firm position, means to move in a slidable manner the prolongations of the wire loop along the shaft of the metallic bar to cause the loop of the wire to fit snugly and to be retracted onto the end of the metallic bar to thoroughly crush tissues engaged in the wire loop, means to unlock and release the metallic bar from its engagement with the loop of the wire, and means to finally retract the wire of the loop to break through the tissues at the very place they have been held and crushed.

24. A surgical instrument, a wire bent to form a distended loop with prolonged ends, a metallic bar, means to lock the metallic bar in a firm position, means to move the prolongations of the wire loop in a slidable manner along the shaft of the metallic bar to cause the loop of the wire to fit snugly and to be retracted onto the end of the metallic bar to thoroughly crush tissues engaged in the wire loop, means to unlock and release the metallic bar from its engagement with the loop of the wire, and means to finally retract the wire of the loop to break through the tissues engaged in the loop at the very place they have been held and crushed.

In testimony whereof I have signed my name to this specification.

B. D. LA FORCE.
